Morris Greenspan, New York, N. Y.

Application February 19, 1952, Serial No. 18,589

Term of patent 14 years

(Cl. D29—28)

To all whom it may concern:

Be it known that I, Morris Greenspan, a citizen of the United States, residing at the Borough of Manhattan, in the county, city, and State of New York, have invented a new, original, and ornamental Design for an Illuminable Floral Vase or Similar Article, of which the following is a specification, reference being had to the accompanying drawing, forming part thereof.

In the drawing:

Fig. 1 is a front elevational view of an illuminable floral vase or similar article, showing my new design;

Fig. 2 is a side elevational view thereof;

Fig. 3 is a rear elevational view thereof;

Fig. 4 is a top plan view thereof; and

Fig. 5 is a sectional view thereof taken along the line 5—5 of Fig. 1.

I claim:

The ornamental design for an illuminable floral vase or similar article, substantially as shown and described.

MORRIS GREENSPAN.
